UNITED STATES PATENT OFFICE

DAVID H. CROSSE, OF CHICAGO, ILLINOIS, ASSIGNOR OF ONE-HALF TO HENRY A. DORMEYER, OF CHICAGO, ILLINOIS

PINCUSHION

Application filed October 17, 1927. Serial No. 226,669.

The present invention relates to improvements in the construction and manufacture of pin cushions and more particularly to pin cushions intended for use on dressing tables and frequently utilized for supporting ornamental figures, dolls, or the like.

The objects of this invention are to provide an improved pin cushion having a substantially rigid base portion and a yielding upper portion; to provide a pin cushion which will have comparatively little contact for engagement with the surface supporting the same; to provide a pin cushion which will be neat and attractive in appearance, durable in use and which may be manufactured at a small cost. Other objects are to provide an improved method of making pin cushions in order to improve the appearance and reduce the cost of the same. Other objects will appear more fully from the following description, taken in connection with the accompanying drawings, in which

Figure 1 is a sectional view of a mold or form showing the inner covering for the pin cushion therein;

Figure 2 is a similar view illustrating the forming of the outer cover for the pin cushion;

Figure 3 is a view similar to Figure 2 showing the outer cover completely formed;

Figure 4 shows the stuffed cushion in place in the outer covering preparatory for the finishing operation; and

Figure 5 is a sectional view showing the finished cushion.

The cushion has an inner cover 6 which is preferably made of crepe paper or other suitable material which may be readily formed to the desired shape. The blank for forming this cover is placed over a mold or form 7, as shown in Figure 1, and then pressed inwardly by a male mold or die member 8, thereby giving it a substantially hemispherical form. Saw dust 9 or other filling material is then placed in the paper cover 6 and a disk 10, preferably made of cardboard is pressed down onto the material, and the edges 11 of the cover are folded in and pasted to the upper surface of the disk 10.

A blank, preferably formed of cloth or other suitable material for forming the outer cover 12, is then placed over the die or mold 7, as shown in Figure 2, and a certain amount of tension is placed thereon by means of a 55 clamping ring 13 so that when the punch or die member 8 presses the same inwardly, the cloth will be stretched to give it a substantially hemispherical shape, as shown in Figure 3. The die member 8 is then removed and 60 the paper covered core or cushion is inserted in the outer cover, as shown in Figure 4. A ring 14 also preferably formed of paper or other suitable material is then inserted in the open end of the die and serves to press the 65 inner paper covered core portion downwardly so that the saw dust or filling material will be packed tightly therein. This ring also fits closely against the outer cover 12 in order to hold it in the core or mold after the ring 70 13 is removed. The outer periphery or edges 15 of the cloth cover are then brought inwardly over the ring 14 and another disk 16, which may be formed of any suitable material, but preferably of paper, is pressed into 75 the ring 14, as shown in Figure 5, and the adjacent or coacting surfaces of the various parts are glued or pasted together to complete the cushion.

The cushion is then completed and ready 80 for receiving pins 17 which may be inserted through the outer and inner covers, as shown in Figure 5.

The cushion is shown in Figure 5 in inverted position, and when it is placed on a 85 dresser or table, the only part coming in contact therewith is the narrow rim or flange 18 which is covered by the cloth cover and which is not apt to collect dirt or grit and scratch or mar the surface of the table as 90 frequently occurs when the ordinary pillow type of cushions are used.

It will, of course, be evident that any suitable finely comminuted material may be used as the filling or stuffing, and it will also 95 be noted that changes may be made in the details of construction or shape of the different parts without departing from the scope of my invention; therefore I do not wish to be limited to the exact construction 100

herein shown and described or to the precise method, except as set forth in the following claims, in which I claim:

1. A pin cushion, comprising a disk, a paper cover engaging with said disk and shaped to give the desired form for the cushion, a filling between the cover and the disk, and a cloth cover enclosing the paper cover.
2. A pin cushion, comprising a circular disk, a substantially hemispherical inner cover having its open end secured to the disk, a filling for said cover, a ring secured to the inner cover, an outer cover enclosing the inner cover and the ring, and a disk engaging with the inner periphery of the outer cover and tending to hold it in engagement with said ring.
3. A pin cushion, comprising a cardboard disk, an inner cover formed of crepe paper with its outer periphery secured to the disk, filling material between the disk and inner cover, a ring secured to the inner cover adjacent to the outer periphery of said disk, an outer cover formed of cloth enclosing said inner cover and having its periphery folded inwardly over the ring and against the inner cover, and a disk inserted in the ring for holding the outer periphery of said outer cover in position, the adjacent parts of the covers, disks and ring being pasted together.

DAVID H. CROSSE.
